Primary Examiner — Karen E Eldridge Powers

(57) **CLAIM**

I claim the ornamental design for a straw fireman's hat, as shown and described.

DESCRIPTION

FIG. 1 is a side elevation view of a straw fireman's hat of the claimed design;

FIG. 2 is a top plan view of the straw fireman's hat of FIG. 1; and,

FIG. 3 is a front elevation view of the straw fireman's hat of FIG. 1.
